UNITED STATES PATENT OFFICE.

ALEXANDER H. REVELL, OF CHICAGO, ILLINOIS.

BATH-TUB.

1,149,687.

Specification of Letters Patent. Patented Aug. 10, 1915.

Application filed March 20, 1915. Serial No. 15,733.

To all whom it may concern:

Be it known that I, ALEXANDER H. REVELL, a citizen of the United States, residing at Chicago, in the county of Cook and State 5 of Illinois, have invented a new and useful Improvement in Bath-Tubs, of which the following is a specification.

This invention relates particularly to the provision of a bath-tub which may be advantageously employed in situations where 10 economy of space is necessary, or desirable.

The primary object of the invention is to provide a bath-tub which may be advantageously arranged with relation to the 15 other fixtures of a bath-room, to economize space, the bath-tub being nevertheless of such a character as to enable the user to lie at full length in the tub, when desired.

The object of the invention is attained by 20 providing a short bath-tub with a covered foot-extension of less height than the main body of the bath-tub, and, preferably, of less width than the main body of the bath-tub. Thus, for illustration, the foot-extension 25 of the bath-tub may be allowed to extend beneath a lavatory bowl, or below the tank of a water-closet and in the rear of the bowl of the water-closet, if desired.

The invention is illustrated in its preferred embodiment in the accompanying drawings, in which—

Figure 1 represents a side elevational view of the improved bath-tub and a front elevational view of a water-closet arranged 35 with relation thereto; Fig. 2 shows the same arrangement, looking at the foot-end of the bath-tub and viewing the water-closet in side elevation; Fig. 3 shows the improved bath-tub arranged with relation to a lavatory or wash-bowl applied to one wall of the bath-room; Fig. 3^a represents a broken longitudinal vertical section through the foot-extension of the bath-tub; Fig. 3^b represents a broken sectional view of the same 45 character, showing a slight modification in the casting of the bath-tub and foot-extension; Fig. 4 represents a plan view of the improved bath-tub with a part of the foot-extension broken away; this construction 50 corresponding with the previously described figures, other than Fig. 3^b; Fig. 5 shows a rear elevational view of the bath-tub illus-

trated in Figs. 1 and 3; and Fig. 6 is a broken horizontal sectional view through the rear portion of the bath-tub.

55

Referring to the several figures, other than Fig. 3^b, A represents a bath-tub provided with an elongated hollow foot-extension A¹ of reduced height; B represents the tank of a water-closet which is connected with a 60 bowl B¹; and C represents a wash-bowl fixture of the type which is ordinarily supported on a wall by means of brackets.

In the illustration given in the main views, the bath-tub A is equipped at its 65 upper or open end with the usual out-turned rim, or flange, 1, which, however, is modified somewhat at the junction with the foot-extension A¹, as will be understood from Figs. 3^a and 4. The foot-extension A¹ is 70 preferably cast integrally with the rear end of the bath-tub.

In the preferred construction which is illustrated, the rear vertical wall of the bath-tub is extended to provide the rear vertical wall 2 of the foot-extension, and the foot-extension is provided opposite the vertical wall 2 with the obliquely extending lateral vertical wall 3. The foot-extension also has the bottom wall 4, the vertical end wall 80 5, and the top wall 6. The lateral vertical wall 3, where the foot-extension is of the reduced width illustrated, may connect with the partial rear vertical end wall 7 of the bath-tub near the longitudinal center of the 85 bath-tub, it being understood, of course, that the foot-extension A¹ is open to the bath-tub at its junction with the main body of the bath-tub. In this construction, it is preferred to locate the water supply pipes 90 8 and the overflow pipe 9 at the front side of the foot-extension A¹, so that the faucet device 10 is disposed just in front of the partial vertical end wall 7.

The bottom of the bath-tub is shown provided with a discharge pipe 11 which may connect with the bottom of the main body of the bath-tub near the longitudinal center of the bath-tub. The bottom of the main body of the bath-tub and the bottom wall of 100 the foot-extension which is at substantially the same level and forms an extension thereof should both incline slightly toward the discharge pipe, as illustrated in Fig. 3^a.

To facilitate the operation of casting the bath-tub with the integral foot-extension, it is preferred to join the top wall 6 and the lateral vertical walls 2 and 3 of the foot-extension to the rim 1 by a hollow embossment, whose rear wall 12 joins the rim in a flush manner, as shown in Fig. 3^a. Said hollow embossment opens into the main body of the bath-tub, so that the rim 1 simply continues across this elevated portion of the foot-extension, and forms virtually an elevated portion of the top wall of the foot-extension, as will be readily understood from Figs. 3^a and 4.

The bath-tub is shown provided with the usual supports, or legs, 13 and the foot-extension is preferably provided with a leg 13^a. In the construction shown in Fig. 3^b, A² represents the body of the bath-tub and A³ represents the foot-extension. In this construction, the rim 1^a continues as a projection entirely around the main body of the bath-tub, and the partial rear end wall 7^a of the bath-tub is extended across the foot extension, and forms a connection between the inner edge of the flange 1^a and the top wall 6^a of the foot-extension. In this construction, some difficulties may be experienced in the molding operation; otherwise, the construction is almost as desirable as the first described construction.

In arranging the fixtures in a bath-room where all available space must be utilized to the fullest possible extent, the foot-extension of the improved bath-tub may be allowed to extend underneath a wash-bowl or below the tank, and in the rear of the bowl of a water-closet, as will be readily understood from the illustrations given.

In accordance with this invention, a substitute for the ordinary short bath-tub may be provided having a hollow foot-extension which opens into the bath-tub at its junction therewith; and a considerable economy in space may be gained. The improved bath-tub may be used with practically the same degree of comfort as a full-length bath-tub of ordinary construction.

It will be understood, from the illustrations given, that a graceful design may be given to the improved bath-tub; and it will also be understood that the improved tub can be produced at a cost which will compare favorably with the full-length bath-tub of ordinary construction.

The foot-extension of the improved tub may be of any desired form, but should be of less height than the body portion of the tub. The width may be made as great as desired, however, depending upon the manner in which the tub is to be arranged in connection with the other fixtures in a bath-room. For illustration, the foot-extension may be broadened in width to the same width as the body of the tub, as illustrated

by the dotted line 14, in Fig. 6. Such a tub would be available for use where the foot-extension has to project under a wash-bowl in the manner illustrated in Fig. 3. In case the foot-extension were thus widened, the water supply and outlet pipes could be arranged in any suitable manner.

It may be added that in the illustrations given the elongated foot-extension is shown covered. The invention is not limited to this feature especially where clearance at the front side only of the foot-extension is desired.

The foregoing detailed description has been given for clearness of understanding only, and no unnecessary limitation should be understood therefrom, but the appended claims should be construed as broadly as permissible in view of the prior art.

What I regard as new and desire to secure by Letters Patent, is:

1. A bath-tub having its rear end provided with a covered elongated hollow extension of reduced height, whose bottom forms a continuation of the bottom of the tub, the top of said extension being low and without encumbrance to afford clearance above it, and being so united to the main body of the bath-tub as to enable the water level to rise above said extension for the purpose set forth.

2. A bath-tub comprising an open-topped main body and an elongated covered foot-extension of reduced height and width, the bottom of the extension forming a continuation of the bottom of the main body, and the top of said extension being so united to the main body of the bath-tub as to enable the water level to raise above said extension.

3. A bath-tub comprising a main open-topped body and an elongated foot-extension projecting from the rear portion of the rear end of the bath-tub and affording clearance at the front side of said foot-extension, the bottom of said extension forming a continuation of the bottom of the main body.

4. A bath-tub comprising an open-topped main body and an elongated hollow foot-extension of reduced height and width projecting from the back portion of the foot end of the bath-tub and affording clearance above and at the front side of said foot-extension, the bottom of said extension forming a continuation of the bottom of the main body.

5. A bath-tub comprising an open-topped flanged bath-tub body having an elongated hollow foot-extension provided with a top wall which is extended upwardly to join the outer edge of the end-flange of the body of the bath-tub, the bottom of said extension forming a continuation of the bottom of the bath-tub body.

6. A bath-tub comprising an open-topped bath-tub body and an elongated covered

foot-extension having a bottom forming a continuation of the bottom of the bath-tub body, said extension being of reduced height to afford clearance and formed integrally with the bath-tub body, and the top of said foot-extension being so united to the main body of the bath-tub as to enable the water level to rise above said foot-extension for the purpose set forth.

10 7. An improved article of manufacture comprising an open-topped bath-tub body provided at its back portion with an elong-

gated foot-extension having an obliquely extending front wall.

8. An improved article of manufacture 15 comprising an open-topped bath-tub body having an elongated hollow tapering foot-extension formed integrally therewith, and having its bottom at substantially the same level as the bottom of the bath-tub body.

ALEXANDER H. REVELL.
